UNITED STATES PATENT OFFICE.

JAMES RICHARD CLAY, OF BLUNDELLSANDS, AND JOHN SCOTT VALENTINE HARRISON, SON, OF WATERLOO, ENGLAND.

CONSTRUCTION OF SHIPS' DAVITS.

Application filed February 16, 1924. Serial No. 693,369.

To all whom it may concern:

Be it known that we JAMES RICHARD CLAY and JOHN SCOTT VALENTINE HARRISON, subjects of the King of England, and residing at Blundellsands and Waterloo, respectively, both in the county of Lancaster, England, have invented Improvements in and Connected with the Construction of Ships' Davits, of which the following is a specification.

This invention has reference to ships' davits mounted and working on horizontal pivots, and their operating gear, wherein the lower part of the davit has a rack which is operated upon by toothed gearing, and this lower part and gearing are disposed and work in a casing adapted to contain a liquid; and the apparatus is so constructed as to prevent the entry of liquid into it from outside, and when the casing is charged with liquid, which in some cases will be of non-freezing character, such as a suitable non-freezing oil, glycerine, or the like, the operating parts will be partly or wholly submerged, lubricated, and protected.

The davit itself, that is the outer and longer part, and the lower or inner and short part within the case, are in some cases, all in one piece; whilst in other cases it may be made in separate parts, separately connected up with a journal or trunnion pin mounted in bearings in the casing. According to this invention the inner or lower end or part of the davit is provided with a quadrant having ordinary spur wheel type of teeth, with which a small toothed spur pinion meshes; and this pinion is coupled up with or formed in one with a large worm wheel, the transverse spindle of which is mounted in bearings in the casing; and meshing with this worm wheel is a worm, which is adapted to be operated through a spindle or the like from outside the casing.

In some cases, in addition to the worm gearing above described, an additional gearing, such as a spur gearing, is employed in connection with the worm shaft, for driving same; namely, on this driving shaft there will be mounted a large spur wheel, say within the casing, while meshing with it is a pinion on a shaft carried in the casing, and revolved or operated from outside by a crank handle or power.

The davit carries outside its supporting bearing, a semicircular or arcuate shield, 55 which works over a correspondingly formed inner frame or case fixed on the casing, parts of which near the centre form bearings to receive the trunnion or pivot pin of the davit; and this part is provided with 60 an arcuate aperture or frame through which the davit can move in its throw. Thus the shield carried by the davit always covers and protects this aperture or slot for all positions of it; and therefore access of spray 65 or water to the casing from the outside is prevented.

The casing, at the inner end, is provided with a roof or hood portion, projecting up from the top of the casing body and forming a separate part attached to the body or main casing, into which portion the upper end of the quadrant will pass when the davit is lowered; and a door or cover is provided on the inner end of the casing, through 70 which the worm shaft bearings and parts may be inserted, and it serves as a means of access to the interior for inspecting the gear, and other purposes as may be required.

The annexed drawings, in connection with 80 which the invention will be further described, show a davit gear having the construction and arrangement of parts above specified.

In these drawings, Figure 1 is a sectional 85 elevation; Figure 2 is an outside end view; and Figure 3 is a cross section showing the gear.

Referring to the drawings, 1 is the casing or box in which the lower part of the davit, 90 and the gear parts are disposed and work; 2, 2^x are the covers of the box 1; 3 is the upper part of the davit arm or davit; and 4 is the quadrant which is within the casing 1 and in the case shown, is in one with or 95 forms part of the davit arm 3.

6 is the trunnion pin of the davit, which in the case shown, is separate from the davit and passes through same or a bush therein, its ends being supported and fixed in bearings 25 on the casing 1, as hereafter explained.

The quadrant 4 has on its lower face a rack 5, consisting of ordinary spur teeth, and meshing with the rack 5, is a small spur pinion 7, mounted on a spindle 8, supported 105

and fixed in bearings 9 on the casing 1, and held in place by plates 8*, secured to the ends of the bearings 9.

The boss or hub 10 of the spur pinion 7 projects out on one side, and on it is keyed or fixed a worm wheel 11, with which meshes a worm 12, formed or fixed on the spindle 13, which is supported in bearings 14, fixed on the inside surface of the casing 10 1 by bolts or other means.

The spindle 13 projects through a cover 15 on the inner end of the casing 1 (which is practically open when the cover is removed), and by the rotation of this shaft, 15 say through a removable hand crank 23, the whole davit gear is operated.

In this gear the only oblique resultant of load or force on members of it, is that between the worm 12 and the worm wheel 20 11; and inasmuch as at this point or part of the train of gearing by its character, the pressure on it at any time is relatively small, the lateral or oblique strain on the teeth of the worm gearing, that is both 25 when operating the gear by hand, when lowering a load on the davit or gear, or when lifting a load; whilst the part of the gear which is subject to the full weight and load, namely, the toothed quadrant 5 and pinion 30 7, has no oblique or lateral thrust imparted to it; that is the pressure or thrust is directly in the planes of the wheels themselves; and consequently no wringing or like objectionable strain or thrust comes upon the davit 35 arm and quadrant.

In the case shown, the worm 12 and its shaft 13 are made in one, and may be assumed to be made of cast or wrought metal; the outer and inner ends being supported in bearings 14 fixed on the inside of the casing; and between one of these bearings 14, and the shoulder 16 on the end of worm 12, there is a ball bearing 17, forming a ball bearing thrust block, against 40 which the endwise pressure on the worm, exerted by the load on the davit (reduced in degree owing to the character of the gearing) is taken; and this as stated is relatively small.

On the worm spindle 13, within the end cover 15, there is fixed a spur wheel 18, with which meshes a small pinion 19, fixed on a short spindle 20 in a bearing 21 on the cover 15, and a suitable bearing 22 on the inside of the casing 1. This spindle 20 projects through the cover 15 similarly as the spindle 13, and it is provided on its outside with a square or flattened end, similar to that of 13, and is adapted to receive a handle 23, which when moving the davits outboard will be on the spindle 13. When the davit is brought up and inboard, the crank 23 is taken from the spindle 13, and placed on the spindle 20, and a further large purchase is thus obtained.

The oil or liquid level in the casing 1 is marked LL.

The trunnion pin 6, as stated, is mounted in bearings 25, on the sides of the casing 1, and is held in place by plates 26, which are fastened to the ends of the bearings by screws, bolts, or the like; and one end of the trunnion is reduced, and projects through the plate 26, and has a sheave or pulley 27 on its end for the purpose of 75 guiding the wire or manilla falls from the boat lowering appliance to the lowering tackles attached to the head of the davit.

The portion of the separate casing cover into which the inner end of the quadrant 80 passes when the davit is down, as indicated by the dotted lines, is marked 2*, and projects up and is fastened onto the top of the casing 1.

The davit 3 has fixed on it an arcuate lid 29, and the sides of the casing project up above the bearings 25 on each side, and are semi-circular in form. This neck portion of the casing through which the davit arm 3 passes, has fixed across it a neck piece 90 in the form of an open frame casting 30, through which the lower portion of the davit arm 3 works, and directly or closely over which the lid 29 fits and works; and the lid having a depending flange which lies over the neck frame 30, a complete cover to the neck of the box 1 is provided in all positions of the davit arm and its lid 29.

The lid 29 may be in halves, as in the case shown, and provided with flanges, so that the two halves may be placed together over the arm, and clamped together and on it, and fixed thereby any suitable means.

The neck frame 30 has a depending flange 105 at each side which comes down on the outside of the circular upwardly projecting side parts of the casing 1, which forms the neck of the casing; and the frame has a lip 31, to which the upper edge of the cover part 2* is attached, and the side edges of the cover are secured by screws or the like to the edges of the neck and the horizontal part of the casing; and its lower end is turned up as shown in Figure 1, and attached to the cover part 2, which projects up as shown, and is bolted or similarly fastened by flanges on the top of the casing.

The backward position of the davit is controlled by a bar 33 across the neck of the 110 casing.

By the trunnion pin 6 being loose, and inserted in position endwise in the bearing 25 of the casing 1, and a bearing sleeve 6* being provided in the boss of the davit, the neck portion of the frame can be formed by carrying up the sides of the casing casting, and the construction is simplified.

While the apparatus given in the drawings shown, is adapted to be actuated by hand, it may be operated by "power", such

as an electric motor or motors connected with the operating parts, and, say, supported on or attached to the casing.

What is claimed is:—

- 5 A ship's davit comprising a casing in which the davit is mounted for movement, mechanism for operating the davit housed within the casing, the casing being formed to provide a neck through which the davit
- 10 extends and in which it swings, a cover for the neck carried by the davit and operating

in all positions of the davit to seal the opening in the neck, said casing being formed with an opening through which a portion of the davit extends in operation, and a housing resting upon the casing to close said opening and receive said extended portion of the davit. 15

In testimony whereof we have signed our names to this specification.

JAMES RICHARD CLAY.

JOHN SCOTT VALENTINE HARRISON.
